LOCOMOTIVE FRAME SUPPORT

Charles Fahlstrom and Hollis Walker, Moline, Ill.

Application November 17, 1938, Serial No. 240,888

23 Claims. (Cl. 105—82)

The present invention relates generally to locomotive frame supports, and more particularly to the spring rigging by which the frame is supported on the journal boxes.

There are two general types of bands in use upon the railroads at the present time for holding the spring leaves together. One of these types is a band such as the plain head or rocker band which rests in a seat constructed upon the top of the spring saddle and, under the weight of the locomotive, is held in place by the seat structure embracing it. The other type, such as the pin rocker band, is one in which the lower portion of the spring band is itself constructed to mate with a corresponding construction upon the spring saddle to accomplish a support, generally pivotal, therebetween which prevents relative horizontal displacement.

In the construction of the spring saddle used with the first type of band, a flat pad of restricted dimensions is provided upon the top of the spring saddle and the structure of the saddle bordering the pad is generally comprised of four upwardly extending projections following the edges of the band and the spring leaves exclusive of any contact with the lower face of the bottom spring leaf. This provides a supporting rest for the spring which prevents horizontal displacement yet permits the spring to rock back and forth on the pad.

With the second type, the spring saddle and the spring band are both conformed to mate in pivotal relationship so that the spring may rock back and forth with the pivotal engagement itself such that relative horizontal displacement between the spring and saddle is prevented under the weight of the locomotive.

There is a Federal ruling requiring that the springs and equalizers of a locomotive be arranged to insure the proper distribution of weight to the various wheels and that the springs be maintained approximately level and in a safe and suitable condition for service.

After a locomotive has been in service for a while, the spring rigging is thrown out of adjustment and the springs out of level by road wear upon the tires and wear taking place between the springs and spring saddles, particularly in the first type of band construction where the springs rock back and forth on a pad and break down the margins and the thickness of the pads supporting them.

In order to correct this condition and to comply with the Federal ruling, it has long been customary in overhauling the spring rigging to

jack up the frame, thereby lift the load from the spring hangers, completely remove the spring hangers, and forge them either to shorten or lengthen them according to individual requirements. This entails a substantial amount of labor and lays up the locomotive for comparatively long periods of time. Then, in event any particular spring hanger is not forged to the proper length the first time, the whole process has to be repeated until each hanger is of the proper length to level the springs and distribute the weight evenly throughout.

In the present invention, it is only necessary to jack up the locomotive to take the weight off the springs. The hangers need not be removed. Proper adjustments can be made without forging operations and the spring rigging can be overhauled without the labor and loss of time entailed in the conventional practices.

Moreover, the invention can be installed and used with all locomotives without altering them since the invention can be placed in operation upon the old equipment as well as the new without any need for additional engineering. Furthermore, the invention eliminates the wear induced by the spring rocking back and forth upon the spring saddle, thus lengthening the time between overhauls, and, with the simplicity of construction provided, the lowness of the cost of manufacture, install and maintain, the present invention accomplishes many new and useful results not heretofore attained.

These being among the advantages and objects of the invention, other and further ones will become apparent from the drawing herein, the description relating thereto, and the appended claims.

Referring now to the drawing:

Fig. 1 is a side elevation of the drive wheel and spring rigging portion of a conventional locomotive as equipped with a preferred form of the invention;

Fig. 2 is a detail view of one of the spring saddle assemblies embodying the invention as illustrated in Fig. 1;

Fig. 3 is a view similar to Fig. 2, illustrating how adjustment can be made to adjust and level the spring rigging of the locomotive at any particular journal or drive box;

Fig. 4 is a section taken upon the line 4—4 of Fig. 3;

Fig. 5 is an exploded view of the preferred form of the invention;

Figs. 6 and 7 illustrate how the invention is

used with spring bands of a different construction.

Broadly speaking, the present invention comprises three characteristic elements employed in various combinations, as shown in the several views of the drawing. Two of the elements accommodate the two general types of spring bands mentioned and one of these two elements, supplied in various thicknesses, serves also as a rigging adjusting plate used interchangeably with one type of spring band and as a spacer in combination with both of the other elements to vary the distance between the journal box and the spring band to level the springs.

Referring now to the drawings in greater detail, a main frame 20 of a conventional locomotive is illustrated in Fig. 1, and, as shown, comprises spaced pedestals 21 interconnecting the upper and lower frame rails 22 and 23 to provide vertical slideways for the truck boxes 24 which are held in place by the pedestal braces 25. The drive wheels are indicated at 26 and support the driving axles 27 for weight bearing purposes through to the truck boxes 24 in which the axles 27 are journaled.

In the particular embodiment shown, the weight of the locomotive on the frame is supported along the top frame rail 22 by means of hangers 28 secured either directly to the frame, as by hanger pins 29, or indirectly to the frame through driver equalizers 30, which are in turn pivotally secured to the frame by the bracket 35. The hangers are secured to the springs 36 at the ends thereof by spring hanger gib 37 which ride upon the top of the springs 36 in spring ends 34.

The leaves of the springs are held together at their common center by a spring band 38 which is supported relative to the driving box 24 by spring saddle assembly 39, illustrating the preferred embodiment of the invention.

In view of the fact that an unbalanced spring rigging arises from relative wear at each wheel, whether it be tire wear or saddle wear, it is apparent that it is preferable to make corrections at a single point for each wheel; i. e., in the assemblage of wheel supported elements where the wear takes place, rather than at two points for each wheel where there is no wear, as conventionally done by forging both hangers for each wheel.

It is in this assemblage of elements between the axle of the wheel and the spring that adjustment and corrections for wear and unbalance is made in the present invention, and from the description thus far it will be seen that the frame 20 of the locomotive may be jacked up enough to relieve the springs 36 so that the gib 37 may be slipped end-wise off the spring ends 34 to free the springs for removal if need be. Adjustments may then be easily made in the elements located between the axle and the spring.

The assemblage of elements provided in the invention is the spring saddle assembly 39 comprising an upper element 40, an intermediate or secondary element 41, and a lower journal box element 42 constructed to straddle the upper frame rail 22 in the conventional manner and to rest upon and engage the journal box 24 in a recess 43.

Whereas the conventional construction provides for a rocking motion between the saddle pad and the spring bands of the first type mentioned, the upper portion of the upper element 40 is constructed to support the spring band 38 without any relative rocking motion therebe-

tween. In accomplishing this the upper face of the element 40 is recessed, as at 46, a sufficient depth to receive the spring band 38 and, as at 44, a sufficient depth to receive the spring leaves 45. Otherwise, the element 40 is conformed to support the spring at two separate points spaced longitudinally of the spring to prevent relative rocking between the spring and the element 40.

Such a conformation is illustrated in Fig. 3 where the spring band has a plain head resting flat against a pad 47 having a flat face. In other instances it is desirable to support the spring independently of the band to avoid complications arising from different band head shapes, in which case the recess 44 is such as to support the lower leaf of the springs 45, and the recess 46 is deep enough to clear the band 36.

Thus in the present invention there is practically no wear taking place between the spring band and the spring seat upon the upper element 40, as is the case with the conventional spring band and saddle arrangement.

The lower face of the unit 40 is provided with a downwardly extending projection 49 which defines a surface of revolution about an axis horizontally transverse the longitudinal dimension of the spring when the spring is normally in place upon the element 40. This surface of revolution comprises, as more particularly shown in Fig. 4, enlarged end portions providing intermediate facing shoulders 51.

The lower saddle member 42 has a recessed groove 52 upon a top face thereof which defines a surface of revolution mating with the surface 35 of revolution of the projection 49, except that the area thereof is less than the area of the projection 49, so that when they are in engagement with each other there is a spaced distance provided between the upper face 53 of the saddle 30 unit 42 and the lower face 54 of the upper unit 40, whereby a rocking motion for the spring is had between the upper unit 40 and the lower unit 42.

In this way, the rocking movement existing conventionally between the spring band and the conventional spring saddle is not only eliminated and, along with it, the wear resulting therefrom, but the rocking motion needed for the spring rigging is provided between two mating surfaces 50 of revolution whereby mutual mutilation will be eliminated and the longevity of parts thereby increased.

In this connection it is well to note that the surface of revolution may be one of a curved line, or a line defining an obtuse angle, it being appreciated that such a construction provides a self centering engagement between the two relative moving parts which is free of transverse play sometimes developed between square shoulders.

The intermediate element 41 shown is one of several flat members of different thicknesses and is provided upon the upper surface thereof with a groove 52a identical with the groove 52 on the saddle member and a downwardly extending projection 55 upon the lower surface thereof, defining a surface of revolution substantially identical and mating with the groove 52. With the surfaces of revolution defined by the projection 55 and groove 52 substantially identical, the lower face 56 of the intermediate element 41 rests flush against the upper face 53 of the saddle unit 42 so that there will be no relative movement therebetween.

Thus whenever the intermediate element 41 is 75 interposed between the upper element 40 and the

lower element 42, the upper element 40 rocks upon the intermediate element 41 in the same manner that it rocks when installed directly upon the unit 42. Consequently, by interchanging intermediate elements 41 of different thicknesses the springs may be re-leveled according to the wear that has taken place.

The spring band 57, illustrated in Figs. 6 and 7, is of the second or roller rocker type wherein a pin 58, having a surface of revolution identical with the recess 52, is interposed between the spring band 57 and the lower element 42 or the intermediate element 41 with the pin 58 resting in the groove 52 or groove 52a. The lower or head portion of the spring band 57 is provided with a groove defining a surface of revolution identical with the surface of revolution of the pin 58, but of an area less than the exposed area of the pin 58 when the pin is in place as described so that the spring band 57 may rock back and forth upon the pin 58. Thus, the intermediate element 42 serves as a spacing means for the second type of spring band construction.

In this way, the intermediate element 41 will serve a double purpose, either as a spacing means for both types of spring bands or as the direct support for the second or roller type spring band. Otherwise, the roller spring band or the top unit 40 may be used directly on top of the spring saddle unit 42 if spacing due to wear is not required.

When it becomes necessary to overhaul the spring rigging of a locomotive and level up the springs, the frame is jacked up and the gibbs removed from the spring ends. The spring is raised and an intermediate member 41 of the proper thickness is inserted between either the elements 40 and 42 or the spring band 57 and the element 42, depending upon the type of band present. However, if an element 41 is already present, it may be removed and replaced by another one of a different thickness to vary the height of the spring above the journal box. The gibbs are then replaced on the spring ends and the frame lowered.

The invention thereby provides a new and useful means for leveling and reconditioning the spring rigging of a locomotive with a minimum of time, effort and materials. No forging operations are required, and it is possible for all the hangers employed in the manufacture of locomotives to be of a uniform length and construction. Spring saddle wear is eliminated and adjustments can be made at one point for each wheel instead of at two.

Consequently, although a preferred embodiment of the invention has been shown and described herein, it will be apparent to those skilled in the art that various and further uses, modifications, and changes may be made without departing from the spirit and substance of the invention, the scope of which is commensurate with the appended claims.

What is claimed is:

1. In combination with a spring support constructed for pivotal movement where it is supported, rigging means adapted for pivotal engagement therewith, and means for altering the height of the pivotal engagement comprising interchangeable members of different thicknesses interlocking with the foregoing elements for supporting the elements against relative horizontal movement.

2. In combination with a spring supporting element, means for supporting the element for pivotal movement about a horizontal axis, and

means for altering the height of said supporting element including interchangeable members for pivotally supporting the supporting element and interlocking it with said means for supporting them with respect to each other against relative horizontal displacement.

3. In a spring rigging for journal boxes the combination of saddle members supported on the boxes and provided with pivotal convolutions upon the upper portions thereof, members constructed upon their lower sides to mate with the convolutions and adapted to support the springs, and interchangeable members of varying thicknesses adapted and arranged upon opposite sides thereof to mate with the upper portions and the lower sides of the saddle members and the second mentioned members, respectively.

4. In a spring rigging for journal boxes the combination of saddle members supported on the boxes and provided with identical pivotal convolutions upon the upper portions thereof, members constructed upon their lower sides to mate with the convolutions and adapted to support the springs, and interchangeable members of varying thicknesses adapted and arranged upon opposite sides thereof to mate with the upper portions and the lower sides of the saddle members and the second mentioned members, respectively.

5. In a spring rigging for a locomotive drive wheel journal box the combination of a member rigidly supported relative to the journal box and offset upon the upper face thereof to provide a pivotal convolution for pivotal movement in one plane only, an interchangeable pad for the spring having a pivotal convolution upon the lower surface thereof mating with the first convolution and supporting the member and the pad a spaced distance for relative pivotal movement.

6. A railroad locomotive spring saddle for a drive wheel journal box and spring comprising a journal box saddle offset to provide a surface of revolution upon the upper face thereof, and interchangeable spring pad means of varying thicknesses for pivotally supporting the spring and provided with an offset upon the lower face thereof defining a surface of revolution mating with the first surface of revolution to support the pad means and the journal box saddle against relative horizontal displacement.

7. A locomotive spring saddle comprising a spring pad member for supporting a spring against longitudinal rocking relation therewith, a driving box saddle member, an interchangeable member of predetermined thickness for insertion intermediate the pad and saddle member to vary the distance therebetween, and means for supporting the three members against relative horizontal displacement when assembled and providing a relative rocking movement between the pad member and the saddle member longitudinally of the spring.

8. A spring rigging construction comprising a saddle member for a journal box, means for supporting a banded spring for pivotal movement about an axis transverse to the spring and remote from the band, and spacer means of a pre-determined thickness rigidly supported relative to the saddle member disposed between the supporting means and the saddle member for supporting them against relative horizontal displacement.

9. In a spring rigging for journal boxes the

combination of saddle members supported on the boxes and provided with surfaces of revolution upon the upper portions thereof, members constructed upon their lower sides to mate with the surfaces of revolution in self centering relationship, and adapted immovably to support the springs relative thereto, and interchangeable members of varying thicknesses adapted and arranged upon opposite sides thereof to mate with the upper portions and the lower sides of the saddle members and the second mentioned members, respectively.

10. In a spring rigging for journal boxes the combination of saddle members supported on the boxes and provided with identical pivotal convolutions upon the upper portions thereof, members constructed upon their lower sides to mate with convolutions such as are upon said upper portions and to support the springs immovably relative thereto, and interchangeable members of varying thicknesses adapted and arranged upon opposite sides thereof to mate with the upper portions and the lower sides of the saddle members and the second mentioned members, respectively.

11. In a spring rigging for a journal box the combination of a member supported relative to the journal box and offset upon the upper face thereof to provide a surface of revolution, a spring supporting element having a surface of revolution upon the lower surface thereof of an area greater than the first surface of revolution, said surfaces of revolution mating together, means insertable between the member and pad and having a contour upon the lower and upper faces thereof mating with the surfaces of revolution respectively, the member and the pad being held thereby a spaced distance from each other for limited relative pivotal movement.

12. A railroad locomotive spring saddle for a journal box and spring comprising a journal box saddle offset to provide a surface of revolution upon the upper face thereof, spring pad means for supporting the spring and provided with an offset upon the lower face thereof defining a surface of revolution mating with and of a greater area than the first surface of revolution to support the pad means and the journal box saddle a spaced distance and against relative horizontal displacement, and an intermediate element insertable between the saddle and pad means and having offsets defining surfaces of revolution on both sides thereof mating each with one of the first two surfaces of revolution, one of said surfaces of revolution upon the pad means having an area substantially the same as the area of one of the other of said first two surfaces of revolution.

13. A railroad locomotive spring saddle assembly for a journal box and spring comprising a journal box saddle offset to provide a surface of revolution upon the upper face thereof extending the full width thereof and spring pad means for supporting the spring and provided with an offset upon the lower face thereof defining a surface of revolution mating with the first surface of revolution for pivotal movement in one plane only, said surfaces of revolution being of a form and relatively different areas to support the pad means and the journal box saddle a spaced distance and against relative axial displacement.

14. In a railroad locomotive spring saddle assembly for a journal box and spring comprising a journal box saddle offset to provide a surface of

revolution upon the upper face thereof, spring pad means for supporting the spring and provided with an offset upon the low face thereof defining a surface of revolution mating with the first surface of revolution, said surfaces of revolution being of relatively different areas to support the pad means and the journal box saddle a spaced distance, and an intermediate element insertable between the saddle and pad means and having offsets upon both sides thereof defining surfaces of revolution of an area substantially the same as the area of one of the first two mentioned surfaces of revolution.

15. In a locomotive spring supporting assembly, a spring saddle member resting upon the journal box astride the frame of the locomotive, a spring band, means for supporting the band for pivotal movement relative to the spring saddle, and means interlocking said spring saddle member and band supporting means for varying the distance between the spring saddle and the band supporting means.

16. In combination with a spring band conformed for pivotal movement where it is supported, rigging means adapted for pivotal engagement therewith, and means for altering the distance between the pivotal engagement and said rigging means and for supporting said means against relative horizontal movement.

17. A railroad locomotive spring saddle for a journal box and spring comprising a journal box saddle offset to provide a surface of revolution upon the upper face thereof, spring pad means for supporting the spring and provided with an offset upon the lower face thereof defining a surface of revolution mating with the first surface of revolution, the area of one surface of revolution being greater than the other to support the pad means and the journal box saddle pivotally with respect to each other and against relative horizontal displacement, and an intermediate element insertable between the saddle and pad means and having offsets defining surfaces of revolution on both sides thereof mating each with one of the first two surfaces of revolution, said surfaces of revolution upon the pad means having substantially the same areas.

18. In a railroad locomotive spring saddle assembly for a journal box and spring, the combination of a journal box saddle, spring pad means for supporting the spring, and an intermediate element insertable between the saddle and pad means, said saddle, pad means and intermediate element having two pairs of offset portions defining mating surfaces of revolution, two of which are of relatively different areas.

19. In a spring rigging, the combination of a saddle member, a spring supporting element capable of pivotally engaging said saddle member, an interchangeable member insertable between the saddle member and supporting element in interlocking relationship for varying the distance therebetween and supporting the assembled elements against relative horizontal displacement.

20. An interlocking shim for railway spring rigging comprising a spacer element having an upper and a lower face, an offset upon the upper face defining a surface of revolution, an offset upon the lower face defining a surface of revolution, said surfaces of revolution having substantially the same dimensions.

21. A spring rigging comprising saddle members for journal boxes, means rigidly engaging springs and supporting the springs for pivotal movement about horizontal axes, and inter-

changeable spacer elements of different thicknesses disposed between and interlocking with pairs of said saddle members and said means respectively for leveling the heights of said supporting means and pivotally retaining the rigging elements against horizontal displacement.

22. In a locomotive spring rigging, the combination of saddle means supported with respect to a wheel journal, a spring band supported with respect to the saddle means and adapted for pivotal movement about a predetermined axis, and means for altering the height of said predetermined axis comprising interchangeable members of different thicknesses supported on said saddle means and pivotally supporting the band for 15 interlocking and supporting said means and band against relative horizontal movement.

23. A locomotive spring saddle comprising a spring pad member for supporting a spring against longitudinal rocking relation therebetween, a driving box saddle member, an interchangeable member of predetermined thickness for insertion intermediate the pad and saddle member to vary the distance therebetween, and means for supporting the three members against relative longitudinal displacement when assembled and providing a relative rocking movement between two of the members longitudinally of the spring.
